PLATFORM SOLE FOR FOOTWEAR

Irving F. Starner, Belmont, Mass., assignor to The
B. F. Goodrich Company, New York, N. Y., a
corporation of New York

Application July 26, 1941, Serial No. 404,187

3 Claims. (Cl. 36—30)

This invention relates to footwear and more particularly to platform soles for shoes, and the invention is especially useful in the manufacture of shoes for sport wear.

It has been proposed heretofore to provide a shoe with a midsole of flexible fibrous material extending the full length of the shoe and having its edge margins covered with cloth or other material as a unit, the midsole being mounted between a shoe upper and an outsole to complete the shoe. However, difficulties have been encountered in the prior constructions due in part to the fact that the fibrous material has had little strength and the marginal covering has had to sustain the entire tensile load between the upper and the outsole. When such covering material in the prior constructions has become worn or milled from exposure to dampness, the shoe often has separated at the heel portion. Furthermore the fibrous material at the heel portion of the shoe where it has been thicker has not properly supported the weight of the wearer with sufficient stability. Furthermore the fibrous material has not been adapted to hold nails or other securing means so that renewal of the heel portion of the sole has been difficult or impossible.

The present invention aims to overcome these difficulties and to provide an improved product.

The principal objects of the invention are to provide an article having stability of the heel portion, to provide for securely anchoring the upper and the outsole at the heel of the midsole, to provide for securely attaching heel lifts in repairing the shoe, to provide greater strength, and generally to provide a neat and simple construction.

These and other objects will appear from the following description and the accompanying drawing.

Of the drawing:

Fig. 1 is a side elevation of a midsole constructed according to and embodying the invention in one of its forms, portions of the upper and the outsole being shown assembled therewith.

Fig. 2 is a longitudinal section of the same with the upper and outsole removed.

Fig. 3 is a view similar to Fig. 2 showing a modified construction.

Fig. 4 is a similar view showing a further modification of the invention.

Fig. 5 is a similar view showing still another form of the invention.

Fig. 6 is a plan view of the midsole of Fig. 1, parts being broken away.

Fig. 7 is a longitudinal section similar to Fig. 5, showing a modification thereof, parts being broken away.

In accordance with the invention a heel block 5 of stiff, nailable material is secured to a flexible platform body of cushioning material extending forwardly thereof to provide the shank and toe portions, and a marginal covering extends about and is suitably secured to the assembled materials, providing a platform sole as a unitary article.

Referring to the drawing, and first to the illustrative embodiment of Figs. 1 and 2 of the drawing, the numeral 10 designates the midsole, 11 the outsole and 12 the upper of a shoe of the platform sole type. The midsole extends the full length of the upper and comprises a heel block 14 of stiff, nailable and desirably substantially rigid material such as wood, a platform cushion 15 of flexible, preferably fibrous material, such as felt or sponge rubber, extending from the toe to a position where its abuts the breast margin of the heel block, and a wedge member 16 of material preferably stiffer than the platform cushion 15 but less stiff than the heel block and of loosely matted paper, fiber, cork, cork composition, or other suitable material. The platform cushion 15 extends over the wedge member and terminates with its upper face flush with the heel 20 seat of the heel block. These parts are joined to each other by adhesion, for example as by the use of rubber cement. A binder strip 17 of strong, thin rubberized fabric may be secured along the lower face of the midsole so as to overlap the wedge member at each end thereof with its ends secured to the heel block and the platform cushion respectively in a position effective to resist separation of the heel block and the cushion platform and wedge members when the 25 sole is bent in walking.

The heel block is flat on its tread face so as to provide a wide cementing or nailing area to contact with the outsole. Its heel seat surface, however, is preferably cupped, as at 18 to conform to and support the heel of the wearer, and preferably has a slight central protuberance 19 at the center to provide a comfortable support.

A marginal covering 20 extends around the entire periphery of the midsole with its upper margin 21 and its lower margin 22 overlapping and cemented to the upper and lower faces of the midsole. This strip is preferably of fabric but may be of leather, artificial leather, rubberized fabric, or any suitable material adapted to match or contrast with the other exposed parts of the shoe.

The heel block 14 of wood or other stiff, nailable material provides a solid support for the ankle of the wearer and resists spreading of the sole, while the material forward thereof provides a flexible cushioning sole for the foot. The upper and outsole may be made up separately and then cemented to the midsole. While in some cases this manner of fastening is sufficient, the heel block provides a secure anchorage to which either the upper or the sole or both may be firmly secured by nails 23, 24 driven into the heel block; thereby relieving the covering 20 of tensile stresses. The wedge 16 supports the arch at the shank of the shoe and assists in securing the cushion sole 15 to the heel block.

In the form of the invention shown in Fig. 3 the construction is similar to that of the first embodiment except that two layers 30, 31 of sole cushion material such as felt are secured together face to face to provide the forward part of the midsole and are spaced apart at the shank to receive a wedge member 32 of stiffer fibrous material such as paper fiber composition. The heel block 33 is similar to the heel block 14, the binder strip 34 is similar to the binder strip 17, and the covering 35 is similar to the covering 20. This construction provides more cushioning at the shank portion of the article.

The form of the invention shown in Fig. 4 is similar to the form shown in Figs. 1 and 2 except that the wedge member 40 is applied above the cushion platform 41 and the wedge member may be made of more resilient material. The heel block 42, binder strip 43, and covering 44 are similar in arrangement and construction to the similar parts 14, 17 and 20 previously described.

In the form of the invention illustrated in Fig. 5, the construction of the platform cushion 50, wedge member 51, binder strip 52, and covering 53 are similar to the corresponding parts of Fig. 1. The heel block 54 is similar to the heel block 14 but this block is of less thickness and a lift 55 of wear resisting material such as leather or rubber soling is secured thereunder to provide additional wear to the shoe. This lift may be made as a separate piece, and may be of uniform thickness or tapered, as desired, or it may be made integral with the outsole as shown for example in Fig. 7 at 55'. Such lift has the advantage of providing additional wear thickness at the heel.

In order to provide greater bendability of the midsole at the ball of the shoe the platform layer 15, or the corresponding layers 30, 41 and 50, may be creased crosswise of the midsole as at 60 to provide determinate bending creases. This may be done after assembly to the parts of the midsole by compressing the assembled material along the desired lines by means of dies under pressure.

In manufacturing the midsole of the invention the heel block is formed by machining from

wood or other suitably stiff nailable material. The cushion platform is cut from sheet stock such as felt or sponge rubber and the wedge member is cut from a block of suitable material such as pressed paper fiber, cork, or other suitable semi-rigid material. These parts are then preferably dipped in rubber cement and dried. When dry the parts are assembled as shown, the binder strip of rubberized fabric is pasted in place, and the marginal covering is applied. After assembly the midsole may be creased as at 60 by applying pressure thereto to increase bendability.

The complete midsole may be assembled as a unit with an outsole and an upper of any style to complete an article of footwear, or the midsole parts may be assembled with other shoe parts to provide such a midsole as will be understood by those skilled in the art.

Variations may be made without departing from the scope of the invention as it is defined by the following claims.

I claim:

1. A platform sole assembly for footwear, said sole assembly comprising a heel block of wood having a concave heel seat formed on its upper face, and a body structure extending forwardly of said block and associated therewith, said body structure comprising a wedge member of relatively stiff material adjacent the breast edge of said heel block, and a platform of cushion material extending forwardly of said heel block over said wedge member with its upper face flush with said heel seat.

2. A platform sole assembly for footwear, said sole assembly comprising a heel block of stiff nailable material having a heel breast face, and a body structure of less stiff material extending forwardly of said breast face, said body structure comprising a wedge member of material less stiff than said heel block at the breast face of the heel block, and layers of platform cushioning material extending above and below said wedge member to said heel block and along each other forwardly of said wedge member, said body structure terminating at the breast face of said heel block.

3. A platform sole assembly for footwear, said sole assembly comprising a heel block of stiff nailable material having a heel breast face and a heel seat surface, a body structure extending forwardly of said breast face, said body structure being thicker than said heel block at said heel breast and being flush with the heel seat surface of said heel block, and a wear-resisting outsole secured along the entire lower face of said assembly, the upper face of said outsole being stepped at the heel breast of said heel block and said outsole being thicker rearwardly of the step to conform with the lower face of the heel block.

IRVING F. STARNER.
